BOAT PROPELLING DEVICE

Isaac Sidney Wells, Laurel, Miss.

Application December 31, 1935, Serial No. 57,020

5 Claims. (Cl. 115—28)

This invention relates to an impeller for small water craft, the primary object of the invention being to provide an impeller of the fish-tail type, and one which may be operated by a rotary movement imparted to the power shaft of the impeller, while the operator is seated in an upright position facing the bow of the boat.

An important object of the invention is the provision of an impelling device of this character which may be operated as a steering means without interfering with the operation of the device as an impelling means.

Another object of the invention is to construct a propelling device which may be turned to a position under the boat, whereupon the device may be operated to impel the boat in a reverse direction. A further object of the invention is to provide means for regulating the stroke or throw of the propeller.

20 A still further object of the invention is to mount the impeller in such a manner that vertical pivotal movement of the impeller will be permitted, thereby insuring against the impeller becoming damaged or rendered inoperative, due to 25 the boat passing over rocks or other submerged obstructions.

With the foregoing and other objects in view, which will appear as the description proceeds, the invention resides in the combination and arrangement of parts and in the details of construction hereinafter described and claimed, it being understood that changes in the precise embodiment of the invention herein disclosed, may be made within the scope of what is claimed, without departing from the spirit of the invention.

Referring to the drawings:

Figure 1 is a sectional view through the stern of a water craft, illustrating an impelling device constructed in accordance with the invention, as 40 mounted therein.

Figure 2 is a plan view thereof.

Figure 3 is an elevational view illustrating the operating handle and power shaft.

45 Figure 4 is a plan view illustrating the propeller as mounted on the propeller bar of the device.

Figure 5 is a perspective view illustrating the lower end of the power shaft showing the impelling bar as connected therewith.

50 Figure 6 is a perspective view of the propeller bar.

Figure 7 is a sectional view taken on line 7—7 of Figure 9.

55 Figure 8 is a sectional view taken on line 8—8 of Figure 7.

Figure 9 is a sectional view taken on line 9—9 of Figure 7.

Figure 10 is a fragmental detail view illustrating a modified form of handle and power shaft.

Referring to the drawings in detail, the water 5 craft or boat is indicated generally by the reference character 5, and is provided with the usual seats 6 to be occupied by the operators of the impelling device.

Extending through the bottom of the water 10 craft or boat, is a power shaft 7 that is encased in the tube 8 that provides a bearing for the power shaft, the tube being secured within the bottom of the boat by means of the threaded plate 9 that in turn is bolted to the bottom of the boat 15 by means of bolts 10. A brace rod 11 connects with the tube 8 and is bolted to the bottom of the boat, holding the tube 8 and power shaft housed thereby, in a slightly inclined position.

On the lower end of the power shaft 8, is a 20 propelling bar 12 that tapers towards the front end thereof, where it is provided with an opening to accommodate the pin 13 that connects the propeller bar 14 to the propelling bar 12.

The propeller bar 14 is formed with a cutout 25 portion 15 extending inwardly from one end thereof, the cutout portion being of a length so that when the propeller bar is connected with the propelling bar there will be a slight clearance between the inner end of the cutout portion 15 and wide end of the propelling bar 12. An extension indicated by the reference character 16 is formed on the wide end of the propelling bar 12 and provides a shoulder to accommodate the propeller bar 14, when the propeller bar is in its normal 30 position. It will be seen that due to this construction, vertical movement of the propeller bar 14 between the extension 16 and bottom of the boat, will be permitted to the end that should the boat pass over a rock or other submerged obstruction and contact with the obstruction, the propeller bar 14 will rise allowing the boat to pass 35 over such obstruction without damage to the impeller.

The propeller bar 14 has its forward end extended upwardly so that when the propeller bar is in its normal position, it will rest in a substantially horizontal position.

An elongated opening 17 is formed in the propeller bar 14 and is designed to accommodate the 45 bolt 18 which passes through the block 19 that carries the yieldable arms 20. The block 19 may be adjusted longitudinally of the elongated opening 17 moving the yieldable arms to adjust them 50 longitudinally of the propeller bar 14.

Mounted on the propeller bar 14 at a point between the elongated opening 17 and free end thereof, is a bearing 21 in which one end of the pin 22 is secured, the pin 22 providing a support 5 for the propeller 23, which is of the fish-tail type. Due to the construction of the propeller and yieldable arms, the propeller, with each movement to the right or left, will strike one of the arms 20 restricting movement of the propeller 23 10 and causing the propeller to move the water craft with which it is connected, forwardly. By adjusting the yieldable arms longitudinally of the propeller bar 14, the stroke or throw of the propeller 23 may be adjusted.

Should it be desired to operate the water craft in a reverse direction, this may be accomplished by rotating the power shaft 7 to bring the propeller bar 14 and propeller 23 supported thereon to a position directly under the water craft, as 20 indicated in dotted lines in Figure 1 of the drawings. By imparting a quarter turn to the shaft 7 alternately in opposite directions, the propeller 23 will be caused to swing laterally to impel the water craft or boat forwardly.

It will of course be understood that handle bars such as shown at 24, are mounted on the upper end of the power shaft 7 whereby movement may be imparted to the power shaft 7.

The handle and power shaft as shown by Figure 10 of the drawings are of a construction to insure against the handle rotating at the upper end of the power shaft. The power shaft is indicated by the reference character 25 and has its upper end tapered as at 26. Keys 27 extend 35 from the tapered portion of the power shaft and fit in grooves formed in the hub and the handle section 28. A nut indicated by the reference character 29 is threaded on the end of the power shaft and engages the handle 28, securing the 40 handle in position.

In view of the foregoing description, it is thought that a further detail description as to the operation of the device is unnecessary.

Having thus described the invention, what is 45 claimed is:

1. In an impeller for water craft, a power shaft extending through the bottom of the water craft, a propelling bar movable with the power shaft, a propeller bar pivotally connected with 50 the propelling bar and adapted to rotate with the propelling bar, said propeller bar having an elongated opening, a block mounted on the propeller bar, a bolt extending through the elong-

gated opening and block, adjustably connecting the block to the propeller bar, yieldable arms on the block, said arms diverging towards the free end of the propeller bar, a pivoted fish-tail propeller mounted on the propeller bar and operating between the yieldable arms, said arms restricting lateral movement of the propeller as the propeller bar moves laterally, causing the water craft to move forwardly, and a handle on the power shaft.

2. In an impeller for water craft, a vertical power shaft extending through the bottom of the craft, a propelling bar on the lower end of the power shaft, a propeller bar mounted for vertical pivotal movement on the propelling bar, a fish-tail propeller pivotally mounted on the propeller bar, handle-bars on the shaft whereby the shaft may be swung laterally and the propeller operated, and means for restricting lateral movement of the propeller.

3. In an impeller for water craft, a vertical power shaft extending through the bottom of the craft, a propelling bar mounted on the lower end of the shaft, a propeller bar pivotally connected with the propelling bar and extending rearwardly beyond the rear end of the craft, a propeller mounted on the propeller bar, adapted to propel the craft when the propeller bar swings laterally, and means for restricting vertical movement of the propeller bar.

4. In an impeller for water craft, an operating shaft extending through the bottom of the craft, a propeller bar, means for pivotally connecting the propeller bar to the shaft whereby the propeller bar may swing vertically, a propeller mounted on the propeller bar and adapted to operate to propel the craft when the propeller swings laterally, and means for restricting vertical movement of the propeller bar.

5. In an impeller for water craft, an operating shaft extending through the bottom of the craft, a propeller bar, means for pivotally connecting the propeller bar to the shaft, yieldable arms mounted on the propeller bar and diverging towards the rear end of the propeller bar, a fish-tail propeller mounted on the propeller bar and adapted to swing laterally between the arms, restricting movement of the propeller, and means for adjusting the arms with respect to the propeller.

ISAAC SIDNEY WELLS.
